Fig. 14

Fig. 13

FIGURE 1 is a side elevational view of a refractor embodying the design,

FIGURE 2 is a plan view of the convex surface of the refractor,

FIGURE 3 is a plan view of the concave surface of the refractor,

FIGURE 4 is an end view of the refractor,

FIGURE 5 is a sectional view taken on line 5-5 of FIGURE 3,

FIGURE 6 is a view of the end of the refractor opposite to that shown in FIGURE 4,

FIGURE 7 is a sectional view taken on line 7-7 of FIGURE 3,

FIGURE 8 is a fragmentary perspective sectional view taken generally on line 8-8 of FIGURE 5,

FIGURE 9 is a fragmentary perspective sectional view taken generally on line 9-9 of FIGURE 3,

FIGURE 10 is a fragmentary perspective sectional view taken generally on line 10-10 of FIGURE 3,

FIGURE 11 is a fragmentary perspective sectional view taken generally on line 11-11 of FIGURE 3,

FIGURE 12 is a fragmentary perspective sectional view taken generally on line 12-12 of FIGURE 6,

FIGURE 13 is a fragmentary perspective sectional view taken generally on line 13-13 of FIGURE 2, and

FIGURE 14 is a fragmentary perspective sectional view taken generally on line 14-14 of FIGURE 3.

I claim:

The ornamental design for a street lighting refractor, as shown.
